UNITED STATES PATENT OFFICE.

EDWARD R. HEWITT, OF MIDVALE, NEW JERSEY, AND AUGUST H. LEIPERT, OF COLLEGE POINT, NEW YORK, ASSIGNEES TO INTERNATIONAL MOTOR COMPANY, OF NEW YORK, N. Y., A CORPORATION OF DELAWARE.

STEEL WHEEL.

Application filed January 4, 1923. Serial No. 610,546.

To all whom it may concern:

Be it known that we, EDWARD R. HEWITT and AUGUST H. LEIPERT, citizens of the United States, residing, respectively, in 5 Midvale, in the State of New Jersey, and College Point, in the borough of Queens of the city of New York, in the State of New York, have invented certain new and useful Improvements in Steel Wheels, of which 10 the following is a specification, reference being had to the accompanying drawing, forming a part hereof.

Steel wheels have to be flexible to afford resiliency and stiff to afford strength against 15 side stresses. These requirements call for opposing properties. Thinness is necessary for resiliency and thickness is necessary for strength. Metals of different properties would ordinarily be selected to satisfy these 20 diverse requirements. In the circumstances, steel wheels have not been satisfactory. Further, the problem of securing a thin disc to the felly has not been solved satisfactorily since known connections have 25 not been of such character as to prevent rupture of metal at points adjacent to the felly where the stresses are greatest.

The principal object of the present invention is to provide an improved steel wheel 30 which is of built-up form and adapted to satisfy the requirements of resiliency and strength and permit the use in its composition of any high grade highly worked metal. A further object is to provide an improved 35 connection between the web of the wheel and the felly which shall itself be of a resilient character and absorb to a great degree the shocks and vibrations which ordinarily would be impressed on the web. This improved connection is of such character as to facilitate the assembling of the parts and further to transmit the turning efforts with greater effectiveness than connections heretofore employed. It will be understood that 40 this turning effort must be transmitted through the metal in the direction of turning, that is, through the thin portion of the metal and, therefore, it has always been something of a problem to insure this 45 transmission without imposing destructive 50 stresses on the associated parts.

In accordance with the invention the improved wheel is built up of a plurality of

web sections in much the manner of a leaf spring to the end that stiffness may be given 55 at the desired points to the necessary degree and resiliency afforded at other points without unduly sacrificing strength for the whole. In its preferred form these component sections will be formed as discs 60 secured to the hub and provided with radial spokes. The improved connection between the web sections, that is, the spokes, and the felly includes resilient blocks, as of rubber, which are carried by the felly and receive 65 the end of the spokes. These blocks absorb to a substantial degree the shocks and vibrations from the tread and reduce stresses to which the web is ordinarily subjected.

The preferred embodiment of the invention will be described with reference to the accompanying drawing in which it is illustrated and in which

Figure 1 is a view in side elevation of a fragment of a wheel embodying the invention, parts being broken out to show the connecting blocks between the spokes and the felly.

Figure 2 is a view in diametrical section through the wheel illustrated in Figure 1.

Figure 3 is a detail view in section at any part of the felly and taken on the plane indicated by the line 3—3 of Figure 1 and looking in the direction of the arrows.

The hub *a* which may be of any approved form has secured thereto various sections *b*, *c*, *d* of steel or other suitable metal which constitute the wheel web. One practical way of building up these sections and securing them to the hub is shown. The hub *a* is 85 formed with a flange *a'* and the sections *b*, *c*, *d* have central openings therein to slide snugly over the hub *a* and be assembled 90 against the flange *a'*. The flanged retaining ring *e* may then be slipped over the hub *a* 95 so as to confine the sections *b*, *c*, *d* between it and the flange *a'*. Rivets *f* or other suitable retaining devices may then be passed through the flanged ring *e*, the hub flange *a'* and the interposed sections *b*, *c* and *d*.

In the illustrated embodiment the sections *b*, *c*, *d* are of disc form having radially extending spoke sections *b'*, *c'*, *d'* respectively, which are of different lengths so as to 100 assume the same relationship as the leaves 105 of a spring. For instance, the spokes *b'* of

the central section b are the longest and extend outwardly into juxtaposition with the felly g (to be described later), while the spokes c' of the two proximate sections c 5 are of less length, and the spokes d' which lie over the spokes c' are of even less length. It will be understood, of course, that the relative lengths, form and numbers of the component sections may be varied as good 10 design may suggest without departing from the spirit of the invention. Stiffness and strength adjacent to the hub are assured by the construction described, while resiliency over all results from the spring-like relation 15 of the juxtaposed sections.

In steel wheels now known great difficulty has been found in securing the thin peripheral sections to the felly with security and strength. The greatest stresses are imposed 20 on the web adjacent to the felly and a tendency to rupture at this point is of common knowledge. A further feature of the present invention is the connection between the component sections of the web and the felly. 25 It is proposed to make this connection of a yielding character, although positive in its nature, in order that shocks and vibrations from the tread may be absorbed and the web thereby relieved to a great degree of the 30 stresses usually impressed thereon. The result of this construction is, of course, that the web itself need not be as stout as heretofore and, accordingly, its inherent resiliency may be greater. As shown, it is preferred 35 to construct the felly g of two sections g', g^2 which meet along a median line of parting and, when assembled, may be secured together by bolting, riveting or locking by appropriate clamping devices. By 40 way of example there has been shown in the drawing a construction in which two circular angle pieces h, h' are laid in under the felly sections g', g^2 and thus secured together at intervals by through rivets i or 45 bolts which pass through a spacer bushing k . The felly sections g', g^2 are formed at proper intervals with complementary flanges g^3, g^4 which, when brought together, constitute a pocket for the resilient connecting 50 block l . In the illustrated embodiment such pockets are of rectangular form to receive a rectangular block l into which extends the rectangular end of one of the spokes b' . The block l may be of rubber or other suitable resilient material. The felly might be 55 made in one piece in which case the boxes for the blocks would be provided with removable cover plates.

In assembling the parts the block l will 60 preferably first be placed on the end of the spoke b' and will be of such form and dimensions that when the felly sections g', g^2 are secured together the complementary flanges g^3, g^4 thereof will confine the block 65 under compression. The advantage of this

is not only that the block l is held so firmly against displacement and thus constitutes such an effective positive connection between the felly and the spoke, but also that its cushioning action is increased and its 70 life greatly lengthened. With such a connection, shocks and vibrations from the tire m , which may be solid, are absorbed to a great degree by the block l and the web sections b, c, d , therefore relieved from the 75 great stresses to which they are ordinarily subjected. This permits the spokes b' to be made comparatively thin and flexible and therefore more resilient. Such stresses which it may have to resist are taken up 80 proportionately by the reinforcing spokes c' and d' which overlie the spokes b' and offer maximum resistance to side stresses thereon. The turning torque which must be transmitted through the spoke b' in the direction of turning, that is, through the thinnest section, passes directly on to the rubber block or from the rubber block on to the spoke and is cushioned in its transmission thereby so that a more effective transmission 85 of this effort is secured than in inflexible connections heretofore known. The compression of the block on to the end of the spoke b' affords a lateral engagement therebetween of large superficial area and the 90 driving stresses are thereby transmitted frictionally, thus relieving the block of cutting stresses which might otherwise be impressed thereon through the thin edge of the spoke b' .

Changes in the form and dimensions and rearrangements of parts may be made without departing from the spirit of the invention provided the principle is employed.

We claim as our invention:

1. A wheel having a web built up of a plurality of juxtaposed metal sections secured together and to the hub, one of the sections extending out to the felly and the other sections being of less diameter and resilient 110 non-metallic connecting means interposed between said first mentioned section and the felloe.

2. A wheel comprising a plurality of metal discs having central openings therein 115 to receive the hub and formed with radially extending spokes of different lengths, the spokes being arranged like the leaves of a spring, respectively, and means to secure said discs to the hub.

3. A wheel comprising a plurality of metal discs secured to the hub and having spoke sections of different lengths mounted in juxtaposition like the leaves of a spring, respectively, the spokes of one of said sections extending to the felly, resilient blocks carried by said last named spokes and means to connect the blocks to the felly.

4. A steel wheel having a web formed as a disc and with radially extending spokes 120

- thereon, resilient blocks engaging the ends of said spokes, and means carried with the felly to connect the felly with the blocks and normally confine them under pressure.
5. A wheel having a web built up from steel plates the central one of which is formed with spokes extending to the felly, two others of which are placed on opposite sides thereof and have spokes in juxtaposition to said first named spokes but of less length, and two others of which are in juxtaposition to said second named plates and having spokes lying in juxtaposition to said second named spokes but of less length.
10. A wheel having a web built up from steel plates the central one of which is formed with spokes extending to the felly, two others of which are placed on opposite sides thereof and have spokes in juxtaposition to said first named spokes but of less length and two others of which are in juxtaposition to said second named plates and having spokes lying in juxtaposition to said second named spokes but of less length.
15. A wheel having a web built up from steel plates the central one of which is formed with spokes extending to the felly, two others of which are placed on opposite sides thereof and have spokes in juxtaposition to said first named spokes but of less length and two others of which are in juxtaposition to said second named plates and having spokes lying in juxtaposition to said second named spokes but of less length.
20. A wheel having a web built up from steel plates the central one of which is formed with spokes extending to the felly, two others of which are placed on opposite sides thereof and have spokes in juxtaposition to said first named spokes but of less length and two others of which are in juxtaposition to said second named plates and having spokes lying in juxtaposition to said second named spokes but of less length.
25. A wheel having resilient blocks carried on the ends of the spokes and means to connect said blocks to the felly.
30. A wheel having metal spokes, resilient blocks carried on the ends of the spokes, a sectional felly to carry the tire, complementary flanges carried with the sections of the felly to form pockets for said blocks which are interposed between the faces of the spokes and the inner faces of the flanges, respectively, and means to secure the sections of the felly together to confine said blocks under pressure and hold them against displacement with respect to the spokes.
35. This specification signed this 2nd day of January, A. D. 1923.

EDWARD R. HEWITT,
AUGUST H. LEIPERT.
